(57) **CLAIM**

The ornamental design for a heater pedestal, as shown and described.

DESCRIPTION

FIG. 1 is an isometric top view of a heater pedestal showing our new design;

FIG. 2 is an isometric bottom view thereof;

FIG. 3 is a bottom plan view thereof;

FIG. 4 is a top plan view thereof;

FIG. 5 is a side elevational view thereof along lines 5-5 of FIG. 1, the opposite side elevational view being identical;

FIG. 6 is a side cross-sectional view thereof along lines 6-6 of FIG. 4;

FIG. 7 is a detail view thereof shown in FIG. 4;

FIG. 8 is a partial sectional view thereof along lines 8-8 of FIG. 4;

FIG. 9 is a side cross-sectional view thereof along lines 9-9 of FIG. 4;

FIG. 10 is a detail view of the sectional view shown in FIG. 6;

FIG. 11 is a detail view of the sectional view shown in FIG. 6;

FIG. 12 is a detail view of the sectional view shown in FIG. 6;

FIG. 13 is a detail view of the sectional view shown in FIG. 6;

FIG. 14 is a detail view of the sectional view shown in FIG. 9;

FIG. 15 is a partial sectional view thereof along lines 15-15 of FIG. 4; and,

FIG. 16 is a detail view of the sectional view shown in FIG. 9.

1 Claim, 11 Drawing Sheets
